UNITED STATES PATENT OFFICE.

COURTNEY C. AVERY, OF AUBURN, NEW YORK, ASSIGNOR TO THE EAGLE WAGON WORKS, OF AUBURN, NEW YORK, A CORPORATION OF NEW YORK.

DUMP-WAGON.

No. 840,601.

Specification of Letters Patent.

Patented Jan. 8, 1907.

Application filed September 23, 1905. Serial No. 279,759.

To all whom it may concern:

Be it known that I, COURTNEY C. AVERY, of Auburn, in the county of Cayuga and State of New York, have invented a certain 5 new and useful Dump-Wagon, of which the following is a specification.

My invention has for its object the production of a dump-wagon which is particularly simple in construction and highly efficient 10 and durable in use; and to this end it consists in the novel combinations and constructions hereinafter set forth and claimed.

In describing this invention reference is had to the accompanying drawings, in which 15 like characters designate corresponding parts in all the views.

Figure 1 is a side elevation, partly broken away, of a preferable embodiment of my invention. Fig. 2 is a front elevation of parts 20 shown in Fig. 1. Fig. 3 is an enlarged sectional view on line A A, Fig. 1, the position of the sections of the bottom when dumping the load being indicated in dotted lines.

The side bars 1 of the frame of my wagon 25 have parts 2 thereof extended upwardly and forwardly to permit the front wheels to turn under the wagon-body. The advance ends 3 of the side bars are disposed in a horizontal plane above and substantially parallel to the 30 main portions of said side bars.

Supplemental frame members 4 are arranged, respectively, beneath the advance ends 3 of the side bars 1, and each consists of a bar having its major portion arranged substantially parallel to the advance end 3 of the corresponding side bar and having one end, 35 preferably the rear end 5, extended upwardly at substantially a right angle to such major portion and fixed by rivets or other 40 means to said advance ends 3. The forward portions 6 of the sides of the wagon-body are fixed to the inner faces of the advance ends 3 of the side bars 1 and the supplemental frame members 4. A frame constructed as described is easily and cheaply manufactured 45 and is of maximum strength.

As best seen in Fig. 2, the side bars 1 are formed of angle-iron of inverted-L-shaped cross-section, the vertical flanges 7 thereof 50 extending downwardly and the horizontal flanges 8 extending outwardly.

9 is a receptacle supported on the rear of the frame of the wagon and forming the major part of the wagon-body, said receptacle

having its opposite sides 10 secured, respectively, to the vertical flanges 7 of the side bars 1, and the lower edges of said sides 10 being substantially flush with the lower edges of the vertical flanges 7. As shown in Fig. 3, the bottom of the receptacle 9 is divided longitudinally along its middle into two opposite sections 11, which are secured at their outer edges to the side bars 1 by hinges having their pivotal pins located, respectively, in the angles of said side bars. 65 Each hinge preferably consists of a substantially U-shaped part 12, depending from the horizontal flange 8 of a side bar 1, and a part 13, fixed to a section 11 in any suitable manner and having its outer end hook-shaped 7c and engaged with the intermediate portion 14 of said U-shaped part 12.

The wagon-body is usually composed of metal, and the sides 10 of the receptacle 9 are extended forwardly, forming the sides 6 of 75 the forward portion of said body. Suitable front and rear wheels 15 and 16 are connected to the wagon-body by any desirable means unnecessary to describe herein.

17 is a winding-drum arranged in front of 80 the receptacle 9, and 18 is an operating member or lever therefor.

19 is a flexible element, as a chain, for normally supporting the sections 11 of the bottom in closed or operative position and for 85 returning the same to such position after dumping the load. The intermediate portion of said element or chain is looped over a wheel 20, suitably supported by the rear end of the receptacle, and the opposite branches 90 of said element are passed beneath engaging members, as rollers 21 22, carried by the sections 11 of the bottom at the opposite ends and the intermediate portions thereof. Said rollers 22 at the intermediate portions of the 95 sections 11 are arranged below the rollers 21 at the ends of the sections for causing the branches of the element or chain 19 to support the sections 11 equally at their ends and intermediate portions. The extremities of the 100 flexible element or chain are suitably secured to the winding-drum 17.

The construction and operation of my dump-wagon will now be readily understood upon reference to the foregoing description 105 and the accompanying drawings, and it will be noted that more or less change may be made in the component parts thereof with-

out departing from the spirit of my invention.

Having thus fully described my invention, what I claim as new, and desire to secure by Letters Patent, is—

1. In a dump-wagon, a frame comprising side bars having parts thereof in advance of the main portions of said side bars extended upwardly and forwardly, the advance ends of the side bars being disposed in a horizontal plane above and substantially parallel to said main portions, and supplemental frame members arranged, respectively, beneath the advance ends of the side bars, each of said members having its major portion arranged substantially parallel to the advance end of the corresponding side bar and rigidly connected to said advance end, substantially as and for the purpose described.
2. In a dump-wagon, a frame comprising side bars having parts thereof in advance of the main portions of said side bars extended upwardly and forwardly, the advance ends of the side bars being disposed in a horizontal plane above and substantially parallel to said main portions, and supplemental frame members arranged, respectively, beneath the advance ends of the side bars, each of said members consisting of a bar having its major portion arranged substantially parallel to the advance end of the corresponding side bar and having one end extended upwardly at substantially a right angle to such major portion and fixed to said corresponding side bar, substantially as and for the purpose set forth.
3. In a dump-wagon, a frame comprising side bars having parts thereof in advance of the main portions of said side bars extended upwardly and forwardly, the advance ends of the side bars being disposed in a horizontal plane above and substantially parallel to said main portions, and supplemental frame members arranged, respectively, beneath the advance ends of the side bars, each of said members consisting of a bar having its major portion arranged substantially parallel to the advance end of the corresponding side bar and having the rear end thereof extended upwardly at substantially a right angle to such major portion and fixed to said corresponding side bar, substantially as and for the purpose specified.
4. In a dump-wagon, side bars having parts thereof in advance of the main portions of said side bars extended upwardly and forwardly, the advance ends of the side bars being disposed in a horizontal plane above and substantially parallel to said main portions, supplemental frame members arranged, respectively, beneath the advance ends of the side bars, each of said members consisting of a bar having its major portion arranged substantially parallel to the advance end of the corresponding side bar and having one end

extended upwardly at substantially a right angle to such major portion and fixed to said corresponding side bar, and the sides of the body of the wagon having their forward portions fixed to the inner faces of the advance ends of the side bars and to said supplemental frame members, substantially as and for the purpose described. 70

5. In a dump-wagon, the combination of a frame comprising side bars formed from angle-iron of inverted-L-shaped cross-section, the vertical flange of each side bar extending downwardly from the horizontal flange thereof, and said horizontal flange extending outwardly, a receptacle supported by the frame and having its sides secured to the vertical flanges of the side bars, the bottom of said receptacle being divided longitudinally into opposite sections, and hinges for said sections having their pivotal pins located, respectively, in the angles of the side bars, substantially as and for the purpose set forth. 75

6. In a dump-wagon, the combination of a frame comprising side bars formed from angle-iron of inverted-L-shaped cross-section, the vertical flange of each side bar extending downwardly from the horizontal flange thereof, and said horizontal flange extending outwardly, a receptacle supported by the frame and having its sides secured to the vertical flanges of the side bars, the lower edges of the sides of said receptacle being substantially flush with the lower edges of said vertical flanges of the side bars, and the bottom of said receptacle being divided longitudinally into opposite sections, and hinges for said sections having their pivotal pins located, respectively, in the angles of the side bars, substantially as and for the purpose specified. 90

7. In a dump-wagon, a frame comprising side bars formed from angle-iron of inverted-L-shaped cross-section, the vertical flange of each side bar extending downwardly from the horizontal flange thereof, and said horizontal flange extending outwardly, a receptacle supported by the frame and having its sides secured to the vertical flanges of the side bars, the bottom of said receptacle being divided longitudinally into opposite sections, and hinges for said sections supported, respectively, by the side bars, substantially as and for the purpose specified. 95

8. In a dump-wagon, a frame comprising side bars formed from angle-iron of inverted-L-shaped cross-section, the vertical flange of each side bar extending downwardly from the horizontal flange thereof and said horizontal flange extending outwardly, a receptacle supported by the frame and having its sides secured to the vertical flanges of the side bars, the bottom of said receptacle being divided longitudinally into opposite sections, and hinges for said sections having their piv- 100

otal pins located, respectively, in the angles of the side bars, each hinge consisting of a substantially U-shaped part depending from the horizontal flange of a side bar, and a part 5 connected to a section of the bottom and having its outer end formed hook-shaped and engaged with the intermediate portion of the U-shaped part, substantially as and for the purpose set forth.

10. In a dump-wagon, the combination of a frame comprising side bars formed from angle-iron of inverted-L-shaped cross-section, the vertical flange of each side bar extending downwardly from the horizontal flange thereof, and said horizontal flange extending outwardly, said side bars having parts thereof in advance of the main portions of said side bars extended upwardly and forwardly, and 15 the advance ends of the side bars being disposed in a horizontal plane above and substantially parallel to said main portions, supplemental frame members arranged beneath the advance ends of the side bars, each of 20 said members having its major portion arranged substantially parallel to the advance end of the corresponding side bar, and rigidly connected to said advanced end, a receptacle supported by the frame and having 25 its sides secured to the vertical flanges of the side bars, the bottom of said receptacle being substantially flush with the lower edges of said vertical flanges of the side bars, and the bottom of said receptacle being divided longitudinally into opposite sections, each provided with engaging 30 members at the ends and intermediate 35 portion thereof, the engaging members at the intermediate portions of the sections being below said members at the ends of the sections, hinges for the sections having their pivotal pins located, respectively, in the angles of the side bars, a winding-drum at one end of the receptacle, and a flexible element secured to the drum and passing beneath the engaging members provided at the ends and intermediate portions of the sections of the bottom, substantially as and for the purpose specified.

10. In a dump-wagon, a frame comprising side bars formed from angle-iron of inverted-L-shaped cross-section, the vertical flange of each side bar extending downwardly from the horizontal flange thereof, and said horizontal flange extending outwardly, said side bars having parts thereof in advance of the main portions of said side bars extended upwardly and forwardly, and 40 the advance ends of the side bars being disposed in a horizontal plane above and substantially parallel to said main portions, supplemental frame members arranged beneath the advance ends of the side bars, each of 45 said members having its major portion arranged substantially parallel to the advance end of the corresponding side bar, and rigidly connected to said advanced end, a receptacle supported by the frame and having 50 its sides secured to the vertical flanges of the side bars, the bottom of said receptacle being divided longitudinally into opposite sections, and hinges for the sections having their pivotal pins located, respectively, in the angles 55 of the side bars, substantially as and for the purpose described.

In testimony whereof I have hereunto signed my name, in the presence of two attesting witnesses, at Syracuse, in the county 60 of Onondaga, in the State of New-York, this 15th day of September, 1905.
